John Revell Gustavus A. J. Schott. By his wife *Hannah P. Harris*

UNITED STATES PATENT OFFICE.

GUSTAVUS ADOLPHUS JOHN SCHOTT, OF BRADFORD, ENGLAND.

LOOM FOR WEAVING CUT PILE FABRICS.

SPECIFICATION forming part of Letters Patent No. 499,474, dated June 13, 1893.

Application filed January 26, 1891. Serial No. 379,030. (No model.) Patented in England January 14, 1889, No. 655.

To all whom it may concern:

Be it known that I, GUSTAVUS ADOLPHUS JOHN SCHOTT, manufacturer, a subject of the Queen of Great Britain and Ireland, residing at Bradford, in the county of York, England, have invented certain Improvements in Looms for Weaving Cut Pile Fabrics, (for which I have obtained Letters Patent in Great Britain, No. 655, dated January 14, 1889,) of which the following is a specification.

My invention relates to an improvement upon my former invention for which I obtained a patent on the 8th day of December, 1891, No. 464,734. In such patented invention I cut each pick of pile weft, as it was being beaten up. Wires, or thin steel knives were attached by one end to a bar and by the other end to the harness, and were pushed toward the reed at the times when the reed would be beaten up. In my present invention, I improve the knives and the method of attaching them to the harness, and of spacing the knives in the knife-bar, and I also provide improved means for actuating the knife-bar.

I will describe my invention with reference to the accompanying drawings:

Figure 1 represents one of the improved knives, with its attachments. Figs. 2 and 3 are respectively front and back end views of the same. Fig. 4 represents a modification in the formation of the knife. Figs. 5 and 6 illustrate the formation of spacing washers, for application to, or between, the front ends of the knives. Fig. 7 illustrates the formation of a harness attachment, for the rear end of a knife. Fig. 8 shows how the knives are applied and worked. Figs. 9 and 10 represent a construction for supporting the ends of the knife bar. Fig. 11 illustrates a modification.

In the drawings, parts which appear in the drawings accompanying my said former invention, in the same or in an improved form, are marked with the same letters of reference.

The knife A represented in Fig. 1, is made of very thin sheet steel, as in my former invention, a being the cutting part and a' the, so termed, wire which passes through the reed. I now make the end a^3 , which is held by the knife bar, in the form of part of a circle. On referring to Fig. 8, it will be seen that the knife bar is composed of two parts,

the bar proper c , and a cap-bar c' , which is screwed or bolted to the bar, c . Partly in the bar proper, and partly in the cap-bar, is formed a channel, or groove, which is of cylindrical, or circular cross sectional formation, to suit the form of the ends, a^3 of the knives. The cross section of this groove includes more than half a circle, so that when the knives are in position, as indicated in Fig. 8, the knives are held by the bar, at the same time the end a^3 of each knife can be raised and lowered, the knife moving partly around the center of the channel in the compound bar $c c'$, as upon a hinge. The knives have to be spaced at a little distance apart, so as to allow the warp threads to pass freely between the knives. This spacing I effect by securing to the end a^3 of each knife a dished washer d made of thin sheet metal. Such a washer is represented in Fig. 6. The washer may be riveted or secured to the flat side of the round end a^3 in any suitable manner. In practice I punch a hole a^4 in the center of the part a^3 and I form a hollow projecting pap d' upon one side of the washer, similar to an ordinary metal eyelet. The pap is inserted in the hole a^4 and is riveted or flanged over in the same manner as when securing an eyelet. When I require wide spaces, as when weaving coarse fabrics, I sometimes attach two washers together, as indicated in Fig. 5, and interpose pairs of the united washers between the knife ends. I hinge the back end a^2 to a hinging piece b made of thin sheet metal. A blank, somewhat in the form represented by Fig. 7, is punched out of the sheet metal, and is perforated. The two wings b' are then bent upward, and toward each other, so as to form jaws, into which the end a^2 of the knife enters. An eyelet passed into the holes b^2 and into a hole formed in a^2 and clenched in the ordinary manner secures the parts together. The end a^2 is not tightly fixed in the jaws in the hinging piece, but is free to turn as upon a hinge. The yarns f, f of the heald or harness are passed through the holes b^3 in the hinging piece. During the working of the loom the ends a^2 of the knives are raised and lowered as indicated in Fig. 8 in which the lay g is represented in its backward position ready for the passage of the shuttle, which for a pile pick would pass over the

lower knives and below the upper knives. As the pile pick would be beaten up the floats of weft would be pushed up toward the cutting part a of the knife and at the time when 5 the reed g' would be pressing the pick of the weft closely up to the last preceding pick, the knife-bar c, c' would be pushed toward the reed by a quick short movement, as described in the specification of my said former invention, the floats of weft being severed at the time when the pick would be tightly held and supported by the reed. For the ground picks, 10 all the knives would be lifted to the upper position, so that the shuttle would pass below all the knives. This is the case with reference to the example illustrated, but it must be understood that I may arrange for all the knives to be kept in the higher position when not in use, knives which are to cut the floats 15 of any pile pick of weft, being in that case lowered for such pick.

When weaving heavy fabrics, the knives made of one piece of thin sheet metal, as in the case of Fig. 1, would be too weak, and if 20 made strong enough the edge at a would be too thick to act as a cutter, without sharpening. To obviate this difficulty I adopt such a formation as indicated by Fig. 4. In this example the parts a^3, a' and a^2 are of two 25 thicknesses, so that the part a^* constitutes a sheath to hold a knife blade a^{10} cut of thin sheet steel. The parts a^3, a^* and the remainder corresponding to parts a', a^2 may be made by cutting out a blank of suitable form and 30 bending it up along the center line, so as to make it double from end to end or the sheath part a^3, a^* may be made of two thicknesses of sheet metal soldered, or brazed to a wire taking the place of a' , as indicated in the end 35 view Fig. 11. The method whereby I impart the said movement to the knife-bar is indicated in Fig. 8, wherein h represents the loom crank shaft, and i the breast beam of the loom, these parts being represented in section. To 40 the inside of the breast beam are secured brackets k' , in which are formed bearings for a rock shaft k . Upon this shaft are fixed two upright levers, of which one appears at l in the said Fig. 8. The levers are fixed near 45 the two ends of the rock shaft, so as to clear the selvages of the fabric which is being woven. The upper end of each lever is connected by means of a link m with the knife-bar which is supported upon slides, or carriers, attached to the loom framing. 50

Fig. 9 and 10 illustrate a suitable construction for supporting the ends of the knife-bar. Each end of the bar is provided with two fingers n, n' which rest upon the bottoms of recesses in a supporting bracket o . The recesses 55

in the bracket o are covered by a steel spring p which keeps the fingers n down in the recesses, and at the same time permits the fingers to slide therein when the knife bar is moved toward the reed. The spring p yields 60 to give the knife-bar a little restrained freedom of upward and downward movement. Upon the rock-shaft k is fixed a lever q which is connected by a link r with a lever s which is mounted upon a fulcrum stud v which is 65 carried by the loom framing. Upon the crank-shaft h is fixed a tappet or wiper t which once in each revolution of the shaft acts upon a bowl s' carried by the lever s . A spring s^2 keeps the bowl in contact with the 70 tappet which is formed to give the bowl a quick push, and is adjusted upon its shaft to give such push at the time of beating up. This push is transmitted to the lever q and by the levers l , and links m to the knife-bar. 75

For convenience of description, and to avoid repetition, I have used the term knife to designate the whole of the device represented in Fig. 1, from a^3 to a^2 although properly speaking the part a is the knife, the part a^3 the 80 head, the part a' the wire, which passes through the reed, and the part a^2 the tail or rear end for connection with the loom harness.

I claim as my invention—

1. The herein described knife for cutting 90 weft pile fabrics in the loom, the said knife having at one end a rounded part for attachment to a bar common to the set of knives, a dished washer attached to this rounded end and a cutting part adjacent to the latter while 95 the opposite end is adapted for attachment to the loom harness, substantially as set forth.

2. In a loom for weaving cut pile fabrics, the combination of a knife-carrying bar, with a cutting knife having a rounded end adapted 100 to fit in a groove in the carrying bar, and having a cutting edge near the said end, and a hinging piece b , carried by the loom harness to which the other end of the knife is hinged, all substantially as and for the purposes set 105 forth.

3. The herein described knife for cutting weft pile fabrics in the loom, said knife having at one end a rounded part for attachment to a carrying bar and perforated at the other 110 end to afford a hinge connection with the harness, with a cutting part adjacent to the said rounded part.

In testimony whereof I have signed my name to this specification in the presence of 115 two subscribing witnesses.

GUSTAVUS ADOLPHUS JOHN SCHOTT.
